CLAIM

The ornamental design for a toaster oven, as shown and described.

DESCRIPTION

FIG. 1 is a perspective view of a toaster oven of the present invention;

FIG. 2 is a front view thereof;

FIG. 3 is a top view thereof;

FIG. 4 is a bottom view thereof;

FIG. 5 is a first side view thereof;

FIG. 6 is a second side view thereof; and

FIG. 7 is a rear view thereof.

The dashed broken lines in the drawings depict portions of the toaster oven that form no part of the claimed design. The dash-dot broken lines define the boundary of the claim and forms no part of the claimed design.

1 Claim, 7 Drawing Sheets
